UNITED STATES PATENT OFFICE.

AMBROSE P. HURT, OF ANDERSON, SOUTH CAROLINA, ASSIGNEE, BY MESNE ASSIGNMENTS, TO HOWARD D. COLMAN, LUTHER L. MILLER, AND HARRY A. SEVERSON, COPARTNERS DOING BUSINESS AT ROCKFORD, ILLINOIS, AS BARBER-COLMAN COMPANY.

DEVICE FOR PLACING TRAVELERS ON THE RINGS OF SPINNING-MACHINES.

1,110,691.

Specification of Letters Patent. Patented Sept. 15, 1914.

Application filed June 21, 1909. Serial No. 503,495.

To all whom it may concern:

Be it known that I, AMBROSE PETER HURT, a citizen of the United States, residing at Anderson, in the county of Anderson and

5 State of South Carolina, have invented certain new and useful Improvements in Devices for Placing Travelers on the Rings of Spinning Machines, of which the following is a specification.

10 As is well known to those skilled in the textile art, the rings of spinning and twisting machines are commonly provided with devices known in the art as "travelers." These travelers are small semicircular wire

15 devices having their edges bent inwardly toward each other, leaving a space therebetween so that the travelers may be caused to embrace the flange of the spinning ring. It is common practice in mills to keep a 20 quantity of these travelers loosely in a suitable receptacle, from which the operative takes a traveler and by holding it between the thumb and finger places it upon the flange of the spinning ring. In such a

25 method the travelers become entangled together in chains or bunches in the receptacle so that it is difficult to separate a single traveler from the mass. In so separating a traveler, a portion of the mass is commonly

30 picked up and shaken more or less violently to release single travelers, and in this way, many of the travelers escape from the mass and fall to the floor, and owing to their small individual value are not picked up.

35 Owing to the fact that these travelers are very small, in many instances not over one-fourth inch at their largest diameter, it is a tedious and troublesome operation to apply them to the spinning ring by hand and re-

40 quires considerable experience on the part of the operator. In so applying travelers by hand, many of them escape from the operator and are not recovered. The aggregate loss of travelers in the manner herein- 45 before mentioned is considerable.

My invention contemplates a device adapted to contain a series of travelers and arranged to quickly and effectively place individual travelers upon the spinning ma-

50 chine rings.

The present embodiment of the inven-

tion comprises a magazine or carrier and means for taking a traveler from the carrier and forcibly springing it upon the flange of the ring.

55

In a copending application Ser. No. 503-494, filed June 21, 1909, which shows a different embodiment, I have broadly claimed the invention, but while the present case is directed to the specific construction, it is 60 to be understood that the present invention is not limited to the details herein shown except as provided in the appended claims.

In the accompanying drawings, Figure 1 is an elevation of a traveler placing device 65 embodying the features of my invention. Fig. 2 is a longitudinal central section through the device. Fig. 3 is a section on the line 3 3 of Fig. 2, showing the device in operative relation to a spinning ring. Fig. 70 4 is a section similar to Fig. 3 but showing the parts in a different position. Fig. 5 is a section on line 5 5 of Fig. 2. Fig. 6 is a fragmentary face view of the forward portion of the device.

75

The present embodiment of the invention comprises a casing A of tubular form, disposed longitudinally within which is a carrier in the form of a rod B adapted to slidably support a series of travelers. For convenience in description, I shall herein term the side of the device adjacent to the spinning ring the face and the opposite side the back.

80

The face of the casing A has a slot a extending longitudinally thereof and the rod B has a spline b' fixed thereto which is adapted to fit in the slot a for holding the rod B in proper position. As shown in Fig. 5, the spline has an enlargement arranged 90 to abut against the inner side of the casing adjacent the slot a and said spline is provided with a threaded screw b² extending outwardly through the slot a, said screw being provided at its outer end with a thumb 95 nut b³ adapted to clamp the spline b' and the rod B in position in the casing A.

95

The rear end of the casing A is provided with a cap A' having an exteriorly screw-threaded flange adapted to be turned into 100 the interiorly threaded end of the casing A. The rear end of the rod B is arranged to fit

within a recess in the inner side of the cap A', and said cap carries an adjusting screw C which is threaded in the rear end of the rod B. By turning the screw C, the rod B 5 may be shifted longitudinally for a purpose to appear hereinafter.

The forward portion A² of the casing A is enlarged somewhat and the extreme forward end thereof is closed by suitable means such 10 as the plug D. Slidably mounted within the enlarged end A² of the casing is a head D' arranged to be normally held in its rear-most position by means of a coiled spring d positioned between said head and the plug 15 D. The rearward movement of the head is limited by a shoulder formed on the casing A.

The rear face of the head D' has a boss d' thereon arranged to extend close to the 20 forward end of the rod B for the purpose of preventing the accidental escape of travelers from said rod. The upper edge of the boss d' is beveled as shown, said edge being adapted to be engaged by the ejecting means 25 to be presently described for the purpose of moving the head D' to one side so as to permit the removal of a traveler. The forward end of the rod B is also beveled in order that 30 the foremost traveler upon the rod will slide by gravity into proper position to be ejected.

The ejecting means comprises a slide F mounted within the enlarged portion A² to move between the forward end of the rod B and the head D', said slide being provided at its outer end with a finger piece 35 for sliding it. A spring G of any suitable form tends to hold the slide F in its outermost position. The inner edge of the slide F is curved as indicated at f to conform to 40 the shape of the travelers. A longitudinal groove e is formed in the face of the enlarged portion A² of the casing A, said groove being adapted to receive the flange H' of the spinning ring H.

45 A transverse slot E is formed through the face of the enlarged portion A in a line with the slide F, through which slot the travelers are ejected by said slide.

The operation of the device is as follows: 50 The cap A' is removed from the rear end of the casing and the carrier rod B is loaded with travelers. The rod is then adjusted in the casing, if necessary, by means of the adjusting screw C to space its forward end 55 at the proper distance from the head D' according to the size of the travelers to be used.

The device is brought into operative relation to the spinning ring by the positioning 60 the forward end thereof so that the groove e receives the flange H' of said ring, as shown in Fig. 3. Upon moving the slide F inwardly, the foremost traveler which has assumed the position directly under said slide 65 will be engaged and the head D' by the cam

action of the inclined upper edge of the boss d' will be moved forwardly to permit the traveler and the slide F to pass between the boss d' and the forward end of the rod B.

As has been previously stated, the spline 70 b' is at the face side of the casing A and the travelers by reason of the fact that they straddle the spline b' when upon the rod, are in such position with reference to the flange H' of the spinning ring that they 75 will straddle the inner edge of the flange when ejected by the slide F, and upon further movement of the slide, the travelers will be sprung over the further edge of the flange H'. 80

It is sometimes desirable to assist the application of the traveler by giving the casing A a swinging movement in the direction of the movement of the traveler to carry the traveler over the further edge of the flange. 85 The extreme position of the swinging movement is indicated in dotted lines in Fig. 4. When the traveler has been ejected from the device, the casing is tipped to cause the travelers to slide by gravity to the forward end 90 of the rod B so that a traveler will come into position to be ejected.

From the foregoing, it will be seen that the device herein disclosed provides a magazine from which travelers may be withdrawn individually so that the loss by waste occasioned by keeping them in bulk is obviated, and in addition to this result, provides an implement with which travelers may be applied to the spinning rings quickly 100 and effectively. 95

I claim as my invention:

1. In a device for placing travelers, in combination, a tubular casing longitudinally grooved upon its outer side to receive a flange of a spinning ring; a rod disposed longitudinally within said casing and adapted to slidably support a series of travelers, one end of said rod being adjacent to said grooved portion and being unobstructed so 105 that travelers may move off said end; a spring-pressed member positioned adjacent said end and adapted to prevent the accidental escape of travelers therefrom; and means adapted to engage a traveler and 110 move it past said spring-pressed member and onto the spinning ring.

2. In a device for placing travelers, in combination, a tubular casing longitudinally grooved upon its outer side to receive a flange of a spinning ring; a rod disposed longitudinally within said casing and adapted to slidably support a series of travelers, one end of said rod being adjacent to said grooved portion and being unobstructed so 115 that the travelers may be moved freely off said end; a spring-pressed member adjacent said end adapted to prevent the accidental escape of travelers therefrom, said member having a cam surface; and a slide arranged 120

125

130

- to engage said cam surface and move said member away to permit the escape of a traveler from the device, said slide being adapted to engage such traveler and spring it onto the spinning ring flange.
3. In a device for placing travelers, in combination, a hollow casing longitudinally grooved upon its outer side to receive a flange of a spinning ring; a traveler-carrying rod within said casing; one end of said rod being adjacent to said grooved portion a spring-pressed head slidable in said casing adjacent said end of the rod and preventing accidental escape of travelers from said rod, and means for ejecting travelers from said casing.
4. In a device for placing travelers, in combination, a hollow casing; a traveler-carrier within said casing, a spring-pressed head slidably mounted within said casing adjacent to the end of said traveler-carrier for preventing accidental escape of the travelers therefrom; and means for ejecting a traveler from said casing.
5. In a device for placing travelers, in combination, a tubular casing longitudinally grooved upon its outer side to receive a flange of a spinning ring; a traveler-carrying rod disposed longitudinally within said casing, the cross-sectional form of said rod corresponding generally to the interior form of travelers; means for preventing accidental escape of travelers from the discharge end of the rod, said end of the rod being adjacent to said groove; and means moving transversely of the rod for ejecting
- a traveler, said ejecting means moving from the side of said rod opposite said groove.
6. In a device for placing travelers, in combination, a tubular casing; a traveler-carrying rod disposed longitudinally within said casing; a spline attached to said rod and running substantially throughout the length thereof; means for preventing accidental escape of travelers from the discharge end of said rod; and means moving transversely of said rod for ejecting a traveler, said ejecting means moving from the side of said rod opposite said spline.
7. In a device for placing travelers, in combination, a casing; a traveler-carrier in said casing, said casing having a longitudinal groove in one face thereof adapted to receive the flange of a spinning ring, and having a slot through said face intersecting said groove; and means for ejecting a traveler through said slot and springing it upon said flange.
8. A device for applying travelers to spinning rings, comprising a body having a tip recessed to engage the flange of a ring, a carrier to supply travelers one by one adjacent the recess of the tip, and a pusher having an irregular edge to discharge the traveler that is adjacent the recessed tip and spring it over the top of the ring.

In testimony whereof I affix my signature in presence of two witnesses.
